CYLINDER LOCK

Samuel A. Liss, Philadelphia, Pa., assignor to
Briggs & Stratton Corporation, Milwaukee,
Wis., a corporation of Delaware

Original application March 31, 1933, Serial No.
663,805. Divided and this application June 29,
1934, Serial No. 733,051

4 Claims. (Cl. 70—46)

This invention relates to improvements in cylinder locks and is a division of the copending application of Samuel A. Liss, Serial No. 663,805, filed March 31, 1933.

It is an object of this invention to provide novel means for removably securing the cylinder of a lock in its casing or mounting member.

More specifically, it is an object of this invention to provide means for removably securing a cylinder in its casing or mounting member, which is mounted at the inner end of the lock and is releasable by a special key inserted into the keyway.

With the above and other objects in view which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawing illustrates one complete example of the physical embodiment of the invention constructed according to the best mode so far devised for the practical application of the principles thereof, and in which:

Figure 1 is a side view partially broken away and in section, illustrating a lock embodying this invention;

Figure 2 is a view similar to Figure 1, showing the manner of releasing the securing means;

Figure 3 is an end view of the lock; and

Figure 4 is a detail perspective view of the inner end of the lock showing the special key in position and the securing means released.

Referring now more particularly to the accompanying drawing, in which like numerals indicate like parts throughout the several views, the numeral 4 designates the casing or mounting member of the lock, bored as at 5 to receive a cylinder 6. The cylinder has a keyway 1 extending longitudinally therethrough to receive a key 8 insertable from the front end of the keyway in the customary manner.

The key 8 is adapted to engage and retract a plurality of tumblers 9 mounted in the cylinder. The tumblers may be arranged to project from the cylinder for interlocking engagement with the casing or mounting member to secure the cylinder against rotation, or as in the aforesaid copending application, may serve as means to control locking members movable radially in the cylinder to and from interlocking engagement with the casing or mounting member.

Inasmuch as the specific manner in which the cylinder is secured against rotation forms no part of this invention, these locking members have not been shown.

The cylinder is secured against endwise movement by a flange 10 at the front end of the cylinder engaging in a counterbore 11, and cooperating with a releasable retaining member 12 at the inner end of the cylinder. The releasable retaining member 12 is in the form of a radially slidable bolt mounted on the inner end of the cylinder and guided for radial motion by an angle plate 13 fixed to the inner end of the cylinder by screws 14.

The rearwardly projecting flange 15 of the angle plate is engageable with lock mechanism (not shown) to transmit rotation from the cylinder to such mechanism.

The releasable locking member or bolt 12, is guided for radial reciprocation by being received in a slot 16 cut into the angle plate and is yieldably urged outwardly to project its outer end over the adjacent end of the casing or mounting member by a spring 17. The spring 17 is confined between, and supported by lugs 18 and 19 struck from the angle plate and the releasable securing bolt, respectively.

To afford metal for the lug 19, the bolt 12 is slotted inwardly from its outer end and the slot formed thereby is in line with the inner end of the keyway to receive the nose of a special key 20. As shown in Figure 2, the insertion of the special key 20, which is longer than the regular key shown in Figure 1, lifts the retaining bolt against the action of its spring 17 to a position at which its outer end clears the inner periphery of the bore 6 and thus frees the cylinder for withdrawal.

It is, of course, understood that the special key, besides releasing the retaining bolt, also acts properly on the tumblers to retract them to their unlocked positions to thus free the cylinder from its casing in all respects.

From the foregoing description taken in connection with the accompanying drawing, it will be readily apparent to those skilled in the art to which this invention appertains, that this invention provides a novel and simple manner of readily removably securing a lock cylinder in its casing or mounting member.

What I claim as my invention is:

1. In a lock, a bored mounting member, a lock cylinder mounted therein and having a keyway extending longitudinally therethrough, a releasable retaining bolt, common means to slidably mount said bolt for radial movement to and from

an operative position engaging the mounting member and for transmitting rotation of the cylinder to mechanism to be actuated, and said retaining bolt being accessible from the inner end of the keyway whereby it is movable to inoperative position by a special key inserted through the keyway.

2. In a lock, a bored mounting member, a lock cylinder rotatable in the mounting member bore and having a keyway extending longitudinally therethrough, means to removably secure the cylinder in the mounting member including a releasable retaining bolt slidable radially across the inner end of the keyway to and from an operative position engaging the mounting member, means fixed to the inner end of the cylinder to so slidably mount the retaining bolt, a spring confined between portions of said retaining bolt and said means to yieldably project the retaining bolt to its operative position, and said retaining bolt having a portion accessible from the inner end of the keyway to be engageable by a special key inserted therethrough for movement to an inoperative position disengaged from the mounting member.

3. In a lock, a bored mounting member, a lock cylinder rotatable in the bore and having a keyway extending longitudinally therethrough, means to removably secure the cylinder in the mounting member including a releasable retaining bolt, means to mount the retaining bolt for radial sliding movement across the inner end of the keyway to and from an operative position engaging the mounting member, a lug struck laterally from the retaining bolt to provide a spring seat, a spring engaging said seat and part of the

means for mounting the bolt to yieldably urge the bolt to its operative position, the formation of the lug leaving a slot in the retaining bolt in line with the inner end of the keyway to receive the nose of a special key inserted into the keyway, and the base of the lug which forms the inner end of the slot providing a shoulder against which the nose of the special key engages to move the retaining bolt against the action of its spring out of its operative position.

4. In a lock, a bored mounting member, a lock cylinder in the mounting member bore and having a keyway extending longitudinally therethrough, and means to removably secure the lock cylinder in the mounting member bore comprising a retaining bolt overlying the inner end of the cylinder, a member detachably secured to the inner end of the cylinder and engaging the retaining bolt to hold the same assembled with the cylinder and slidable radially thereof past the keyway, spring means connected with the retaining bolt and said member to yieldingly urge the bolt to a position projecting one end beyond the edge of the cylinder and into operative engagement with the mounting member, cooperating abutments on the retaining bolt and said member to limit outward projection of the retaining bolt by said spring means, and means on said retaining bolt accessible from the inner end of the keyway to enable movement of the retaining bolt to inoperative position disengaged from the mounting member by a special key inserted through the keyway.

SAMUEL A. LISS. 35
